HONING TOOL

Maurice N. Prange, Detroit, Mich.

Application April 13, 1942, Serial No. 438,793

7 Claims. (Cl. 51—184.4)

This invention relates generally to honing or lapping tools and refers more particularly to tools of this type having a plurality of circumferentially spaced abrasive elements support for radial adjustment either inwardly or outwardly relative to the axis of the tool.

One of the principal objects of this invention is to improve the adjusting means for the abrasive elements so as to enable the diameter of the tool to be varied throughout a wide range of travel and, at the same time, permit adjustment of the abrasive elements to within very close limits of a pre-selected diameter in the range of adjustment of the tool.

Another object of this invention is to provide adjusting means for the abrasive elements which is not only simple and compact in construction, but which is also capable of being located for convenient manipulation by the operator.

A further object of this invention is to substantially increase the wear and performance of the abrasive elements by providing each element with a backing formed of a material carefully selected to control the wear of the abrasive elements during operation of the tool.

A further object of this invention is to provide a driving connection between the cage of the hone and the drive shaft which permits the cage to float to some extent and align itself with the bore being honed.

The foregoing, as well as other objects, will be made more apparent as this description proceeds, especially when considered in connection with the accompanying drawings, wherein:

Figure 1 is a side elevational view of a honing tool constructed in accordance with this invention;

Figure 2 is a longitudinal sectional view taken on the line 2—2 of Figure 1;

Figure 3 is a cross sectional view taken on the line 3—3 of Figure 2;

Figure 4 is a cross sectional view taken on the line 4—4 of Figure 2;

Figure 5 is a cross sectional view taken on the line 5—5 of Figure 2;

Figure 6 is a cross sectional view through one of the abrasive elements and the associated supporting structure;

Figure 7 is a cross sectional view taken on the line 7—7 of Figure 1;

Figure 8 is a detail elevational view of one of the stone holders; and

Figure 9 is a sectional view taken on the line 9—9 of Figure 8.

The lapping or honing tool selected herein for

the purpose of illustrating the invention comprises a revolvable member or cage 10 having circumferentially spaced longitudinally extending slots 11 of sufficient width respectively receive the holders 12 for the abrasive elements 13. The opposite ends of the cage 10 are respectively closed by suitable heads 14 and 15 which preferably threadedly engage the cage to enable the same to be readily disassembled.

The abrasive elements 13 are adjustable radially with respect to the axis of rotation of the cage and for accomplishing this result a pair of scrolls 16 and 17 are respectively rotatably supported on the cage at opposite ends of the holders 12. The inner surfaces of the scrolls are provided with helical teeth and these teeth respectively engage corresponding teeth formed on opposite ends of the holders. The arrangement is such that rotation of the scrolls in one direction moves the holders 12 radially outwardly with respect to the cage and rotation of the scrolls in the opposite direction moves the holders 12 radially inwardly relative to the cage. This adjustment of the abrasive elements 13 is accomplished by the means to be presently described and is important because it enables adjusting the tool to various different diameters.

The cage 10 is rotated by a head 18 comprising principally two parts 19 and 20. The part 19 is formed with an annular flange 21 concentric with the axis of rotation of the head and threaded for detachable engagement with the part 20. The part 20 is provided with a tapered spindle 22 adapted to engage a suitable driving mechanism not shown herein.

The part 19 is also provided with a hub 23 adapted to telescopically receive one end of a torque transmitting tube 24 and secured to the tube 24 by means of the fastener elements 25. The opposite end of the tube 24 is internally threaded for detachable connection with a coupling sleeve 26 adapted to project into a hub 27 formed on the head 15 of the cage 10. Upon reference to Figure 4 it will be noted that a plurality of pins 28 project radially outwardly from the coupling sleeve 26 in spaced relation to each other circumferentially of the sleeve 26 and, respectively, project into longitudinally extending slots 29 formed in the hub 27. The slots 29 open through the free end of the hub 27 to enable the pins 28 to be readily inserted into the same and accidental disengagement of the pins from the slots 29 is prevented by a sleeve 30. The sleeve 30 is slidably mounted on the coupling 26 and threadedly engages the inner surface of the hub 29.

The above construction provides a driving connection between the head 18 and the cage 10.

It has previously been stated that the abrasive elements 13 are adjustable radially with respect to the cage 10 by rotating the scrolls in one direction or the other depending on whether it is desired to increase or decrease the effective diameter of the tool. In accordance with this invention, the above adjustment is accomplished by means conveniently accessible for manipulation on the driving head for the tool.

Upon reference to Figure 2 it will be noted that a sleeve 31 surrounds the annular flange 21 on the head in concentric relation to the axis of rotation of the head and this sleeve is formed with an internal helical tooth 32. One end of the sleeve is rotatably supported on the part 19 of the head and the opposite end of the sleeve is provided with teeth 33 normally engaging co-operating teeth on a collar 34 which, in turn, is splined on the part 20 for sliding movement relative to the head toward and away from the sleeve 31. The collar 34 is normally urged in a direction toward the sleeve 31 by a spring 35 and, accordingly, the sleeve 31 normally rotates as a unit with the driving head 18.

The sleeve 31 is connected to the scrolls 16 and 17 by reduction gearing 36 suitably supported on the driving head 18 within the confines of the annular flange 21. In detail, a bracket 37 is secured to the part 19 of the driving head 18 within the annular flange 21 and this bracket supports a shaft 38 for rotation about an axis laterally offset from and extending substantially perpendicular to the axis of rotation of the driving head 18. A pair of gears 39 are respectively secured to opposite ends of the shaft 38 and extend through adjacent slots in the annular flange 21 for meshing engagement with the helical tooth 32 on the inner surface of the sleeve 31.

Upon reference to Figure 3 it will be noted that a worm 40 is secured to the shaft 38 between the bevel gears 39 and meshes with a worm gear 41 which, in turn, is secured to a stub shaft 42 supported on the bracket 37 for rotation about an axis coincident with the axis of rotation of the head. It follows from the above that rotation of the sleeve 31 in opposite directions effects a corresponding rotation of the stub shaft 42 through the medium of the reduction gearing 36.

One end of the stub shaft projects into the tube 24 and is preferably polygonally shaped as indicated by the reference character 43. The polygonally shaped end 43 of the shaft telescopes within a correspondingly shaped bore formed in a coupling 44, with the result that the coupling is rotated as a unit with the stub shaft 42. The coupling 44 is pinned or, otherwise, secured to one end of a shaft 45 having the opposite end detachably secured to a shaft 46. The shaft 46 extends axially through the cage 10 and is secured to both of the scrolls 16 and 17.

Referring now to the operation of the adjusting mechanism, it will be noted that when the operator desires to vary the diameter of the tool the collar 34 is moved against the action of the spring 35 to release the sleeve 31 from its driving connection with the head 18. The sleeve 31 is then rotated either clockwise or counterclockwise depending on whether it is desired to increase or decrease the diameter of the tool. Rotation of the sleeve 31 imparts a rotative movement to the stub shaft 42 through the reduction gearing 36 and the shaft 45 correspondingly ro-

tates the scrolls 16 and 17 to radially adjust the abrasive elements 13 relative to the cage 10. The above adjusting mechanism enables the diameter of the tool to be varied throughout a wide range of travel and, owing to the nature of the reduction mechanism 36, permits adjusting the abrasive members to within very close limits of any preselected diameter in the range of adjustment of the tool. Moreover, the sleeve 31 for effecting the desired adjustment is readily accessible by the operator and, accordingly, the adjustment may be made with the minimum loss of time. In addition, it will be noted that the construction of the tool and associated driving mechanism is such as to enable the parts to be readily assembled and disassembled.

Referring now more particularly to Figure 6 of the drawings, it will be noted that the abrasive elements 13 are each provided with a backing 50 in the form of a flat strip of material having different wearing characteristics than the abrasive element. The backing strip 50 may be formed of relatively soft or ductile metals, although I prefer to form the strip of fibrous material which is considerably tougher than the abrasive elements and not only minimizes chipping and breaking of the abrasive elements but also improves the finish of the surface of the work being honed by the abrasive elements. In any event, the strip 50 extends for substantially the full length of the abrasive element and is cemented or, otherwise, secured against a side of the abrasive element adjacent the work performing face of the latter element. In the present instance, the strip is secured on the leading side of the abrasive element and one longitudinal edge of the strip is arranged substantially flush with the work performing surface on the abrasive element.

For the purpose of convenience in installation of the abrasive elements and associated backing strips, both of the latter are preferably secured in a channel shaped sheet metal clip 51. The abrasive elements are preferably cemented in their respective clips and the latter are adapted to fit in the holders 12 for the abrasive elements.

Although any suitable means may be provided for clamping the clips 51 to their respective holders 12, nevertheless, I have shown in Figures 8 and 9 a preferred construction for accomplishing this result. In detail, each stone holder 51 has a pair of lugs 52 respectively secured to opposite ends of the base portion of the clip. The lugs 52 project into slots 53 formed in the adjacent ends of the associated stone holder and are threaded for receiving clamping screws 54. The inner ends of the clamping screws 54 respectively abut the adjacent ends of the stone holders 12 and frictionally hold the clips in place.

What I claim as my invention is:

1. In a tool of the class described, a revolvable supporting member, abrasive elements mounted on said supporting member in spaced relation to each other circumferentially of the member for movement radially of the axis of said member, means for adjusting the abrasive elements radially with respect to the axis of rotation of the supporting member including a revolvable shaft having a worm gear thereon, a second revolvable shaft supported with its axis extending transversely to the axis of the first shaft and having a worm meshing with the worm gear, a toothed wheel secured to the second shaft, a rotatable sleeve supported in concentric relation to the first shaft and having an internal helical tooth

meshing with the teeth on said wheel for driving the first shaft in opposite directions upon rotation of the sleeve in opposite directions, and means connecting the first shaft to the abrasive elements for adjusting the latter radially of the supporting member.

2. In a tool of the class described, a revolvable supporting member, abrasive elements mounted on the supporting member in spaced relation to each other circumferentially of the member for movement radially of the axis of said member, means for driving the supporting member including a revolvable head having an annular portion concentric with the axis of rotation of the head and having a slot through the annular portion, a revolvable shaft supported on the head in axial alignment with the axis of rotation of the head and projecting into the annular portion, a toothed wheel also rotatably supported on the head in the annular portion thereof and projecting through the slot in said annular portion, a sleeve surrounding the annular portion and having an internal helical tooth meshing with the teeth on said wheel for rotating the wheel in opposite directions upon rotation of the sleeve relative to the head in opposite directions, means operatively connecting the toothed wheel to said shaft for rotating the latter, and means operatively connecting the shaft to the abrasive elements for adjusting the latter radially of the supporting member.

3. In a tool of the class described, a revolvable supporting member, abrasive members mounted on the supporting member in spaced relation to each other circumferentially of the member for movement radially of the axis of the member, means for rotating the supporting member including a revolvable head having an annular portion concentric with the axis of rotation of the head and having a slot through the annular portion, a shaft supported on the head in axial alignment with the axis of rotation of the head and projecting into the annular portion of the head, a worm gear secured to the shaft within the annular portion of the head, a second shaft supported on the head in the annular portion of the latter and having a worm meshing with the worm gear, a toothed wheel secured to the second shaft and projecting through a slot in the annular portion of the head, a sleeve supported on the annular portion of the head for rotation relative thereto and having an internal helical tooth meshing with the teeth on the toothed wheel for rotating the first named shaft in opposite directions upon rotation of the sleeve relative to the head in opposite directions, and means operatively connecting the first named shaft to the abrasive elements for adjusting the latter radially with respect to the supporting member.

4. In a tool of the class described, a revolvable

supporting member, abrasive elements mounted on said member in spaced relation to each other circumferentially of the member for movement radially of the axis of said member, means for driving the supporting member including a revolvable head having an annular portion concentric with the axis of rotation of the head and having circumferentially spaced slots through the annular portion, a shaft supported on the head in axial alignment with the axis of rotation of the head and projecting into the annular portion, a worm gear secured to the end of the shaft in the annular portion, a second shaft having a worm meshing with the worm gear, a pair of toothed wheels secured to the second shaft and respectively extending through the slots in the annular portion of the head, a revolvable sleeve surrounding the annular portion and having a helical internal tooth meshing with the toothed wheels on the second shaft, means connecting the sleeve to the head for rotating the sleeve as a unit with the head and releasable to permit rotation of the sleeve relative to said head, and means connecting the first named shaft to the abrasive elements for radially adjusting said elements relative to the supporting member upon rotation of the first named shaft in opposite directions.

5. In a tool of the class described, an elongated abrasive element having a work performing surface and a flat strip of fibrous backing material extending for substantially the full length of the abrasive element and cemented to a side of said element adjacent the work performing surface with one longitudinal edge substantially flush with the work performing surface of the abrasive element.

6. In a tool of the class described, an elongated clip substantially channel shaped in cross section and having an abrasive element therein, a holder having a channel for receiving the clip, a pair of lugs respectively secured to opposite ends of the base portion of the clip and projecting through slots in the base portion of the channel in the holder, and clamping screws threadedly engaging the lugs and respectively engageable with opposite ends of the holder to clamp the clips in assembled relation with the holder.

7. In a tool of the class described, an elongated clip substantially channel shaped in cross section and having an abrasive element therein, a holder for the clip, a pair of lugs respectively projecting from opposite ends of the clip through registering slots in the holder, and releasable clamping elements respectively carried by the lugs and engageable with adjacent portions of the holder to removably secure the clips in assembled relation with the holder.
